LIFE PRESERVER HOLDER

Capitola E. Blow, Hartford, Conn.

Application December 19, 1936, Serial No. 116,805

3 Claims. (Cl. 114—190)

The present invention relates to new and useful improvements in life preserver holders of the type generally similar to that constituting the subject matter of U. S. Patent No. 924,881, issued 5 on June 15, 1909.

The primary object of this invention is to provide, in a manner as hereinafter set forth, a life preserver holder of the aforementioned character embodying novel means for automatically returning the hinged rack to its raised out of the way position after the life preservers have been discharged or removed therefrom.

Other objects of the invention are to provide a life preserver holder of the character described 15 which will be comparatively simple in construction, strong, durable, highly efficient and reliable in use, compact and which may be manufactured at low cost.

All of the foregoing and still further objects 20 and advantages of the invention will become apparent from a study of the following specification, taken in connection with the accompanying drawings wherein like characters of reference designate corresponding parts throughout the 25 several views, and wherein:

Figure 1 is a view in end elevation of a life preserver holder embodying the present invention.

Figure 2 is a view similar to Fig. 1 showing the 30 rack in lowered position.

Figure 3 is a view in front elevation of the invention.

Figure 4 is a bottom plan view of an end portion 35 of the invention.

Figure 5 is a detail view in perspective of one of 40 the rack connecting links.

Figure 6 is a detail view in vertical longitudinal 45 section through one of the lever or arm attaching brackets.

Referring now to the drawings in detail, it will 50 be seen that the reference numeral 1 designates the joists which support the deck 2 of a boat. Hingedly mounted for swinging movement in a vertical plane on certain of the joists 1, as at 3, is a rack which is designated generally by the 55 reference numeral 4. The rack 4 comprises end members 5 on the lower edges of which slats 6 are secured, said end members 5 being attached to the hinges 3. Mounted on the slats 6 are partitions 7, which together with the end members 5, 55 are adapted for abutting engagement with the lower edges of the adjacent joists 1. As illustrated to advantage in Fig. 3 of the drawings, the construction and arrangement is such as to provide compartments 8 for the reception of life preservers 9 when the rack 4 is in raised position.

Secured to the joists 1 which carry the hinges 3 are brackets 10 to which arcuate arms 11 are pivotally connected, at one end, as at 12. The arcuate arms 11, it will be noted, are mounted for swinging movement in a vertical plane on the 5 brackets 10. The brackets 10 are grooved or channeled longitudinally, as at 13, (see Fig. 6) to accommodate the arcuate arms 11.

The free end portions of the arms 11 are connected to the end members 5 of the rack 4 10 through the medium of links 14. As best seen in Fig. 5 of the drawings, the links 14 comprise oppositely turned end portions 15 which are journaled in the arms 11 and the end members 5 of the rack 4. Coil springs 16 connect the free ends 15 of the arms 11 to extensions 17 which project longitudinally from one end of the brackets 10. Additional coil springs 18 connect the rack 4 to the joists 1 which carry the brackets 10 and the hinges 3, said coil springs 18 being connected at 20 one end to the end members 5 of said rack 4. Anchored to the rack 4 at an intermediate point and depending therefrom is a pull rope 19 having a suitable handle 20 on its lower end.

It is thought that the operation of the invention will be readily apparent from a consideration of the foregoing. To discharge or remove the life preservers 9 from the compartments 8, the rack 4 is swung downwardly on the hinges 3 against the tension of the coil springs 16 and 18 25 through the medium of the pull rope 19. After the life preservers have been discharged or removed and the rack 4 has been released, the springs 16 return the arms 11 to raised position and the springs 18 swing said rack 4 upwardly on 30 the links 14. It will thus be seen that a compact but strong and durable arrangement has been provided for returning the rack 4 to its raised, 35 out-of-the-way position after the life preservers have been removed.

It is believed that the many advantages of a life preserver holder constructed in accordance with the present invention will be readily understood and although a preferred embodiment of the device is as illustrated and described, it is to 45 be understood that changes in the details of construction and in the combination and arrangement of parts may be resorted to which will fall within the scope of the invention as claimed.

What is claimed is:—

1. A life preserver holder comprising a rack hingedly mounted beneath a support for swinging movement in a vertical plane, arcuate arms pivotally connected, at one end, to the support, links pivotally connecting the rack to the free end 55

portions of said arms, coil springs connected to said arms for yieldingly supporting said arms in raised position, and coil springs connected to the rack for yieldingly supporting said rack in raised position on the arms.

2. A life preserver holder of the class described comprising a rack hingedly mounted for swinging movement in a vertical plane beneath a support, brackets rigidly secured on the support and including longitudinal extensions at one end, arcuate arms pivotally connected, at one end, to the other ends of the brackets, said brackets having longitudinal grooves therein accommodating the arcuate arms, links pivotally connected, at one end, to the free end portions of the arcuate arms and at their other ends to the rack, coil springs connected, at one end, to the bracket extensions and at their other ends to the free end portions of the arcuate arms for yieldingly supporting said arcuate arms in raised position, and coil springs connected, at one end, to the support and at their other ends to the rack for yieldingly supporting rack in raised position relative to the arcuate arms.

3. In combination with a deck structure including spaced joists, a rack hingedly mounted

for swinging movement in a vertical plane beneath said deck structure, said rack including end members hingedly connected to certain of the joists, slats mounted on said end members, partitions mounted on said slats, said partitions and the end members being adapted for abutting engagement with the lower edges of the joists and, in conjunction therewith, defining compartments for the reception of life preservers, and means for yieldingly securing the rack in raised position beneath the deck structure, said means including brackets rigidly secured on said certain joists, said brackets comprising extensions projecting longitudinally from one end, substantially arcuate arms pivotally connected, at one end, to the other ends of said brackets, the bracket having longitudinal grooves therein accommodating the arms, coil springs connected, at one end, to the extensions and at their other ends to the free end portions of the arms, links pivotally connected, at one end, to the free end portions of the arms and at their other ends to the end members of the rack, and coil springs connected, at one end, to said certain joists and at their other ends to the end members of the rack.

CAPITOLA E. BLOW. 25
